UNITED STATES PATENT OFFICE.

EVERETT L. HAYNES, OF CHICAGO, ILLINOIS.

DESIGN FOR A BADGE.

40,415.

Specification for Design.

Patented Dec. 28, 1909.

Application filed November 6, 1909. Serial No. 526,673. Term of patent 3½ years.

To all whom it may concern:

Be it known that I, EVERETT L. HAYNES, a citizen of the United States, and a resident of Chicago, in the county of Cook and State of Illinois, have invented a new, original, and ornamental Design for a Badge, of which the following is a specification, reference being had to the accompanying drawing, forming part thereof, in which the figure is a front view of a badge of my design.

I claim:—

The ornamental design for a badge, as shown.

EVERETT L. HAYNES.
